UNITED STATES PATENT OFFICE.

HERBERT JACK, OF HUNTINGTON PARK, CALIFORNIA.

DESIGN FOR A RADIATOR ORNAMENT.

Application filed December 26, 1928. Serial No. 29,417. Term of patent 3½ years.

To all whom it may concern:

Be it known that I, HERBERT JACK, a citizen of the United States, residing at Huntington Park, in the county of Los Angeles and State of California, have invented a new, original, and ornamental Design for Radiator Ornament, of which the following is a specification, reference being had to the accompanying drawings, forming part thereof.

Fig. 1 is a front elevational view of a radiator ornament showing my new design.

Fig. 2 is a side elevational view of the radiator ornament.

I claim:

The ornamental design for a radiator ornament as shown.

HERBERT JACK.
